UNITED STATES PATENT OFFICE.

HENRY R. DUDLEY, OF BOSTON, MASSACHUSETTS, ASSIGNOR OF ONE-HALF TO DAVID W. THOMPSON, OF BOSTON, MASSACHUSETTS.

TURN-DOWN COLLAR.

1,180,022.

Specification of Letters Patent. Patented Apr. 18, 1916.

Application filed September 23, 1914. Serial No. 863,204.

To all whom it may concern:

Be it known that I, HENRY R. DUDLEY, a citizen of the United States, and resident of Boston, in the county of Suffolk and State 5 of Massachusetts, have invented certain new and useful Improvements in Turn-Down Collars, of which the following is a specification.

This invention has for its object to provide a turn-down apparel collar adapted to 10 permit a four-in-hand necktie to slip freely endwise between the neck band and the turn-down or outer portion of the collar so that the tie may be adjusted endwise in knotting 15 it without the usual difficulty due to the binding of the collar on the tie at the back portion of the wearer's neck.

The invention consists in the improvements which I will now proceed to describe 20 and claim.

Of the accompanying drawings forming a part of this specification: Figure 1 represents a view of the inner side of a turn-down collar embodying my invention; Fig. 2 represents a side view of the outer side of the collar, a part of the turn-down portion being 25 broken away; Fig. 3 represents an enlarged section on line 3—3 of Fig. 1; Fig. 4 represents a sectional view showing the parts of 30 the collar in the relative positions they occupy during the laundering operation; Fig. 5 represents a view similar to Fig. 4, showing the tab hereinafter referred to bent outwardly and downwardly from the line of 35 its attachment to the neck band of the collar.

The same reference characters indicate the same or similar parts in all the views.

In the drawings, 12 represents the neck 40 band portion of a turn-down collar, and 13 represents the outer or downwardly turned portion of the collar, sometimes called the flap portion, the collar being, excepting as hereinafter specified, of ordinary or any 45 suitable construction, and the neck band portion being provided with the usual end buttonholes 14 and central buttonhole 15.

In carrying out my invention I apply to 50 the neck band 12 the tab 16 preferably of fabric similar to that used for the neck band. Said tab is narrower than the neck band and is first laid flat upon the latter in the position indicated by Fig. 4. That edge portion of the tab which is then the lower

edge portion is then united to the neck band 55 by a longitudinal row of stitches 17 extending lengthwise of the band and about midway between its upper and lower edges and close to the said lower edge portion of the tab. The width of the tab is such that its free or 60 unattached portion extends from the stitches 17 nearly to the upper edge of the neck band 12, its attached edge portion being considerably above the rear buttonhole 15.

The tab occupies the position shown by 65 Fig. 4 while the collar is being laundered, so that the side of the tab which is outermost is rendered smooth and anti-frictional by the laundering iron and the starch with which the collar is treated. After the laun- 70 drying operation the free portion of the tab is bent outwardly and downwardly along a line close to and parallel with the stitches 17, as indicated by Figs. 3 and 5, to form a tie-guiding fold located below the upper 75 edge of the neck band 12 and below the usual fold of the collar, and a tie-guiding lip projecting downwardly from said tie-guiding fold between the parts 12 and 13 of the collar. The said tie-guiding fold and lip prevent 80 a necktie 18 from rising to contact with the fold of the collar. The side of the tab on which the anti-frictional face is formed by the laundering operation constitutes a continuous antifrictional tie-guiding surface 85 which bears on the upper edge and outer side of the necktie when the tab is adjusted for use, so that the necktie is adapted to slip freely endwise while in contact with the tab.

The tab 16 constitutes a flexible guard rib 90 carried by the neck band portion as a permanent part thereof, said rib being arranged intermediate the height of the neck band portion, and spaced a substantial distance from the upper and lower edges thereof. 95 In other words, the said flap or guard rib is located a substantial distance between the line of connection between the band portion and the flap portion where the fold of the collar is made and also located a substantial 100 distance above the lower edge of the neck band portion.

Having described my invention, I claim:

1. A turn-down collar having a tie-guiding tab adapted to lie flat against the upper 105 portion of the outer surface of the neck band and attached to the latter by a longitudinal row of stitches passing through that

edge portion of the tab which is the lower edge portion when the tab is flat, the exposed side of the flat tab being adapted to be rendered antifrictional by an iron during the 5 laundrying operation, the tab being bent along a line close to and parallel with said stitches to form a tie-guiding fold located below and parallel with the fold of the collar, and adapted to prevent the tie from 10 rising to contact with the collar fold, and a tie-guiding lip projecting downwardly from the tie-guiding fold between the neck band and the outer portion of the collar, the said fold and lip having a continuous antifrictional tie-guiding surface formed by the 15 antifrictional laundried side of the flat tab.

2. In a turned-down collar, a neckband portion and a flap portion, a flexible guard-rib carried by the neckband portion as a 20 permanent part thereof and arranged inter-

mediate the height of said neckband portion and spaced a substantial distance from the upper and lower edges thereof.

3. In a folding collar, a neckband portion, a flap portion, a flexible guard-rib permanently connected to the neckband portion and at the outer side thereof, said guard-rib being located a substantial distance below the line of connection between the band portion and the flap portion where the fold is 25 made and also located a substantial distance above the lower edge of said neckband portion.

In testimony whereof I have affixed my signature, in presence of two witnesses.

HENRY R. DUDLEY.
